UNITED STATES PATENT OFFICE.

HENRY VICTOR PERREAULT, OF LOWELL, MASSACHUSETTS.

LOCK, BOLT, AND LATCH RELEASING DEVICE.

1,086,848.

Specification of Letters Patent.

Patented Feb. 10, 1914.

Application filed August 19, 1911. Serial No. 644,908.

To all whom it may concern:

Be it known that I, HENRY VICTOR PERREAULT, a citizen of the United States, residing at Lowell, in the county of Middlesex and Commonwealth of Massachusetts, have invented a new and useful Improvement in Lock, Bolt, and Latch Releasing Devices, of which the following is a specification.

10 This invention relates to lock, bolt and latch releasing devices, particularly, for independently-hinged, outwardly-opening double exit doors of buildings for large assemblies of people, as school-houses, churches 15 and public halls. One door of such a pair, sometimes called a "standing" door, is less frequently used than the other or "swing" door and is ordinarily held in the closed position by "Cremorne" bolts, arranged at the 20 top and bottom of the inner face of said standing door and simultaneously operated by the same lever. The swing door usually carries a key-operated or "dead bolt" lock or a spring latch or both, to engage the 25 standing door. When nervous or excited persons attempt to open one or both doors, they frequently draw the Cremorne bolts and crowd the doors outward without retracting the dead bolt or spring latch of the 30 swing door. School-children, carelessly or mischievously, often act in the same manner. When the doors are thus opened, without first disengaging the doors from each other, the keepers of the bolt and latch are 35 broken, the lock and latch are bent or broken and the adjacent stiles of the doors and the center bead are broken,—some or all of these mishaps are certain to occur,—entailing a considerable loss for repairs and replacement of broken parts of costly doors, locks 40 and latches.

The objects of this invention are to make it impossible to draw the Cremorne bolts without simultaneously disengaging the lock 45 bolt and latch-bolt from the standing door, and to facilitate the opening of the doors, when both are required to be opened immediately, in case of fire or panic and without the use of a key.

50 In the accompanying drawing, Figure 1 is an inside or rear elevation of adjacent parts of a pair of double swinging doors provided with my improvement, parts of the

doors and of the cases of the locking and unlocking devices being removed, the latch and dead bolt being in engaging position; Fig. 2, a similar view, the latch and bolt being retracted; Fig. 3, a vertical cross section on the line 3-3 in Fig. 4 of the rack-case and the push-rods, showing in end elevation the racks and in side elevation the pinions which engage them; Fig. 4, a front elevation of the rack-case and its contents, the cover of the case being removed; Fig. 5, a rear elevation of the doors provided with my improvement. The remaining figures show the invention used merely to disengage a spring-protruded latch; Figs. 6-9 illustrating a convenient means of applying a latch-releaser to doors where the latch and Cremorne bolts are already in place; Figs. 6, 7, 8 and 9 corresponding respectively in a general way to Figs. 1, 3, 4 and 5; Fig. 6 being a rear elevation with parts of the door and guide-box removed, showing the gears and racks operated by the movement of the Cremorne bolt-rods arranged at a distance from the T or lever by which said Cremorne bolts are operated; Fig. 7, an end elevation of the parts shown in Fig. 8, and Fig. 8, a rear elevation showing the racks and the connecting mutilated pinion which operate the push-rod, the rear of the case being removed, and Fig. 9, a rear elevation of double doors provided with the devices shown in Figs. 6, 7 and 8; Figs. 10, 11, and 12 also correspond in a general way to Figs. 1, 3, 4 and 5, except that they show the preferred construction where the Cremorne bolts and latch are to be applied with my device to new doors; Fig. 10 being a rear elevation of the doors, part of the door and rack-case being broken away and the mutilated pinion being attached directly to the shank of the T or Cremorne bolt-operating lever and engaging a rack secured to the push-rod, the latch being closed; Fig. 11, an elevation of the free edge of the swinging door fitted with the rack, pinion and push-rod shown in Fig. 10, the side of the rack-case being removed; Fig. 12, a front elevation of the rack-case, push-rod, rack and pinion which engages said rack, the rear of said case being removed.

In Figs. 1, 2, 5, 6, 9, and 10, A denotes a "standing" door or door which is intended to remain closed when only one of the doors

is required and A¹, the always used or "swing" door; B B¹, the Cremorne bolts carried by the standing door A and entering keepers b b¹ above and below said door A and connected by rods b² b³ to means of operating them simultaneously, said means being represented as consisting of a pinion b⁴ engaging two racks b⁶ b⁷ arranged on opposite sides of said pinion, within a guide-box 5 B², and each jointed to one of said rods, and a T-shaped handle or T b⁵, the shank of which is rigidly secured to said pinion, so that said bolts may be thrown into or out of engagement by turning said T in the 10 proper direction. These parts are of any usual construction and operation except as hereinafter stated.

In Figs. 1-5 the swing door A¹ carries a lock or lock-case C having a "dead" bolt c capable of being operated by a suitable key C¹ in the usual manner and normally prevented from being otherwise opened (except as hereinafter stated) by tumblers c¹ (pivoted in the usual manner on a stationary 20 stud c²) which engage a stump c³ carried by the dead bolt c, until said tumblers c¹ are raised by a suitable key to bring the gates or slots c⁴ of all the tumblers into the same plane with said stump in the usual manner 25 when the further turning of the key moves the dead bolt longitudinally into locking or unlocking position. Into this lock I introduce a tumbler-lifter for raising the tumblers when the bolt is in locking position 30 (Figs. 1 and 2). This tumbler-lifter consists of a slide D, represented as arranged parallel with said bolt c and as guided between said bolts and the bottom of the lock-case C, (the inner end of said tumbler-lifter 35 having a downward projection d which rests on said bottom) and by the bottom of the bolt-opening c⁵. The outer end of the slide is flush with the outer end of the bolt and with the face of the lock when said bolt is 40 in its retracted position but is moved outward with said bolt when the latter is projected from the case, said bolt having in its under side a slot c⁶, into which a pin d¹ in the top of said slide projects, so that when 45 said bolt is projected the inner end of the slot being against said stud forces said slide outward with said bolt, until the bolt comes to rest. A spring-lever D¹ pivoted upon a stud c⁷ on the inside of the back of the case 50 C passes down freely between two pins d² d³ projecting laterally from the bolt and enters a V-shaped slot d⁴ in the side of the slide in such a manner as to project the outer end of the slide beyond the outer end of the bolt 55 60 when the bolt is thrown outward until the pin d¹ reaches and is stopped by striking the outer end of the slot c⁶. The slide D is provided with an inward and downward incline d⁵ upon which or immediately above which

rest downward projections c⁸ with which the tumblers c¹ are provided when the slide is projected to its greatest extent, these tumbler projections c⁸ respectively being of such length that when the slide is retracted into the case by pressure from without, all said tumblers are raised to the proper height to allow the bolt to be retracted by the backward pressure of the spring-lever D¹ upon the pin d³, said lever at first yielding sufficiently to allow the tumblers to be raised 70 cut off engagement with the stump of the bolt. When the bolt and slide are fully retracted the tumbler-projections c⁸ spring down into a notch d⁶ in the top of the slide, as shown in Fig. 2, allowing the tumblers to 75 return to their normal stump-engaging position and preventing the slide from being projected from the case C without the use of the key applied in the usual manner, the sides of the tumbler projections and the end 80 of said notch engaged thereby being substantially vertical.

In Figs. 1 and 2 a pinion E is represented as fast on the stem of the T-handle b⁵, concentrically therewith, and in engagement 90 with the rack f which slides horizontally and carries a push-rod f² which is crowded against the slide D when the handle b⁵ is operated to withdraw the Cremorne bolts B, B¹, the doors A, A¹ being closed and locked, 95 the push rod f², pushing said slide into the lock and lifting the tumblers, then forcing back the dead bolt. In Figs. 1 and 2 the swing door A is represented as provided with a latch G arranged in the case C and 100 normally protruded from said case by a spring g in the usual manner. This latch G is pushed into the case simultaneously with the dead bolt by means of another push-rod f³, carried by a rack f¹ arranged parallel with 105 the push-rod f² and rack f and operated in a similar manner by a pinion E¹ in engagement with and driven by the pinion E above described. Thus both the push-rods, the rack and the pinions are operated by the 110 turning of the T-handle simultaneously with the drawing of the Cremorne bolts B B¹ to unlock and unlatch the doors from each other. These racks and pinions are arranged in a metallic case H or box let into the door 115 and covered by the case which contains the racks b⁶ b⁷ and the pinion b⁴ which operate the Cremorne bolts. The push-rods f² f³ project from the case H into the mortise a in the standing door which receives the latch head 120 G and dead bolt c when the doors are locked to each other and the top and bottom and back of said mortise a are lined by a metallic guide-plate a² which is held in place by the usual strike plate a⁴ which covers the mouth 125 of said mortise, said guide-plate a² having holes a⁵ in which said push-rods f² f³ have a sliding fit and by which they are guided.

In Figs. 6, 7, 8, a latch-bolt G and spring g of the ordinary construction and as above described are shown without a lock and the same letters indicate corresponding parts as in figures previously described. In Figs. 6, 7 and 8, the Cremorne bolts are operated as above described and to the lower bolt-rod b³ is secured as by set-screws b⁹ a clamp b¹¹ adjustable on the bolt-rod b³ and having an arm b¹³ fixed thereon which arm reaches into a hole f⁴ in a vertical rack f⁵ and causes said rack to reciprocate with said bolt-rod b³, that is to rise when the lower bolt B¹ is raised. The vertical rack f⁵ engages one member e of a compound mutilated gear E² and the other member e¹ of said gear engages a horizontal rack f⁷ from which project arms f⁸ f⁹ which enter and have a sliding fit in horizontal grooves i i¹ (shown in dotted lines in Fig. 8) in the sides of a carrier-block I, which is adjustably connected to said rack f⁷ by said arms f⁸ f⁹ and by an adjusting screw i² which turns without advancing in said rack and enters a screw-threaded hole in said block to vary the distance between the push-rod f³ rigidly secured to said carrier-block parallel with said rack according to the thickness of the standing door to which these parts are applied. The racks f⁵ f⁷ and gear E² are arranged in a metallic case H¹, similar to the case H above described, which case H¹ is represented as let into the door A flush with the face thereof and is preferably covered by a plate h on which the clamp b¹¹ slides. The carrier-block I is outside of the case and the push-rod carried thereby is directed by a guide-plate a², similar to that shown in Figs. 1 and 2, against the latch G when the Cremorne bolts are withdrawn.

The construction shown in Figs. 6-9 is adapted to be applied where the Cremorne bolts are already in use and the guide-box is not suitably located for the direct attachment of the push-rod actuating pinion to the stem of the T.

The remaining figures (10-12) show a push-rod f³ carried by a horizontal rack f¹ actuated by a gear E² fast on the stem of the T handle, the parts indicated by the same letters of reference being as heretofore described in construction and operation. The racks b b⁷ which are jointed to the bolt-rods must be arranged to engage the opposite side of their operating pinion or the rack f¹ must be placed in engagement with the under side of the gear E².

I claim as my invention:—

1. The combination in a lock, of a case, a dead bolt, tumblers to engage said bolt and to retain said bolt in its locking position, a tumbler-lifter arranged in said case and means arranged wholly outside of said case for operating said tumbler-lifter to disen-

gage said tumblers from said bolt and to retract said bolt. 65

2. The combination in a lock of a dead bolt, provided with a stump, tumblers to engage said stump and to retain said bolt in its locked position, each of said tumblers being provided with a gate to permit the passage of said stump, a tumbler-lifter, means for projecting and retracting said lifter, connecting means between said lifter and all said tumblers to bring the gates of all said tumblers to the same plane with said stump by the retraction of said lifter and means for guiding said lifter parallel with said bolt. 70

3. The combination in a lock of a dead bolt, tumblers to engage said bolt and to retain said bolt in its locking position, a tumbler-lifter adapted to disengage said tumblers from said bolt and subsequently to retract said bolt by the retraction of said lifter 80 and yielding connecting means between said lifter and said bolt to project the outer end of said lifter beyond the outer end of said bolt by the locking of said bolt. 85

4. The combination of a lock adapted to 90 be carried by one of a pair of swinging doors and having a dead bolt and tumblers to engage and retain said bolt in its locked position, a tumbler-lifter adapted to disengage said tumblers from said bolt and carried by said lock, yielding connecting means between said bolt and said lifter, to project the outer end of said lifter beyond the outer end of said bolt by the locking of said bolt, a pushing device carried by the other of 100 said doors and means for operating the same to force said lifter into said lock, to disengage said tumblers from said bolt and subsequently to unlock said bolt. 95

5. The combination of a lock adapted to 105 be carried by one of a pair of swinging doors and having a dead bolt and tumblers to engage and retain said bolt in its locked position, a tumbler-lifter adapted to disengage said tumblers from said bolt and carried by said lock, yielding connecting means between said bolt and said lifter, to project the outer end of said lifter beyond the outer end of said bolt by the locking of said bolt, a pushing device carried by the other of 110 said doors, Cremorne bolts carried by said last-named door and means for simultaneously operating said lifter to release said dead bolt and for retracting said Cremorne bolts. 115

6. The combination in a latch-releasing device for double swinging doors, of Cremorne bolts adapted to be carried by one of said doors, means for simultaneously operating said bolts, a pinion operatively connected with said bolts, a rack engaged by said pinion and a push-rod carried by said last-named rack, with a spring latch, car- 120

ried by the other of said doors, in alinement with said push-rod when said doors are closed, and adapted to engage said first named door and to be pushed out of such engagement by said push-rod simultaneously with the disengagement of said Cre-

In witness whereof, I have affixed my signature in presence of two witnesses.

HENRY VICTOR PERREAULT.
